(57) CLAIM

The ornamental design for an animal coat as shown and described.

DESCRIPTION

FIG. 1 is a right side elevation view of the animal coat, shown fastened in a first configuration and in condition of use for clarity of disclosure; and

FIG. 2 is a right side elevation view thereof;

FIG. 3 is a front, right perspective view of the animal coat of FIG. 1, shown in the first configuration;

FIG. 4 is a front elevation view thereof;

FIG. 5 is a rear elevation view thereof;

FIG. 6 is a right side elevation view thereof;

FIG. 7 is a left side elevation view thereof;

FIG. 8 is a top plan view thereof; and

FIG. 9 is a bottom plan view thereof.

FIG. 10 is a top, rear perspective view of the animal coat, shown unfastened in a second configuration;

FIG. 11 is a top plan view thereof;

FIG. 12 is a bottom plan view thereof;

FIG. 13 is a front side view thereof;

FIG. 14 is a rear side view thereof;
